GATE

Application filed May 12, 1930. Serial No. 451,682.

Our invention relates to a safety gate more particularly to safety gates for use in controlling the crossing traffic at railroad grade crossings and consists in the combinations, arrangements, and constructions herein shown and described.

It is an object of our invention to provide a railroad crossing gate which, if moved to its operative position upon the passage of a vehicle thereunder, will yield upon encountering said vehicle to allow passage of said vehicle from beneath the gate, and that will automatically assume its normal position upon the passage of said vehicle from beneath the gate.

A further object of our invention is to provide a gate of the type described which will permit escape of a vehicle entrapped by the arm of the gate on the railroad track by means of so constructing the arm of said gate that the same will yield upon engagement with a vehicle on the track and will automatically return to its normal position upon passage of said vehicle.

25 A still further object of our invention is to provide a device of the type described which has few parts, which is simple to manufacture and which does not get out of order easily.

30 Other objects and advantages will appear as the specification proceeds and the invention will be more particularly defined in the appended claim.

Our invention is illustrated in the accompanying drawing forming a part of this application, in which:

Figure 1 is a sectional view of our gate mounting and operating means therefor.

Figure 2 is a detail plan view of a portion 40 of the device,

Figure 3 is a detail elevational view of the same portions of the device, and

Figure 4 is a sectional view on the line 3—3 of Figure 3.

45 Figure 5 is an enlarged sectional view illustrating the pivotal connection between the main and auxiliary gate arms.

In Figure 1 of the drawing, we have indicated a tower support 10 of any conventional structure, upon opposite sides of which

there is mounted a pedestrian gate 11 and vehicular gate 12, these gates being of length to extend across their respective roadways when in lowered operative positions.

For mounting the oscillating arms of our gate to control the vehicle traffic upon the crossroad as well as the pedestrian traffic on the sidewalks adjacent said crossroad, we have provided shafts or axles 24 and 25, respectively. The shafts 24 and 25 are positioned in the upper portion of the tower in the embodiment shown, although they may be positioned at any desired point at which it is wished to have the gate placed when in operative and inoperative positions.

The shafts 24—25 include arms 13 and 14 respectively, operatively connected with links 15 and 16 of a fluid pressure operating means generally indicated at 17. It will thus be seen that motion will be imparted to the shafts 24—25 upon actuation of the fluid pressure means for moving the gates 11 and 12 to an upward or downward position.

Integrally secured to the shaft 24 are the arms 26 and 27 of the vehicle control gate 12. These arms 26 and 27 suitably brace and support between them a block 29 or other suitable supporting means for the gate 12. It will be understood from an examination of Figures 2, 3, and 4 that this gate 12 includes an arm 28^a which is pivoted on the vertical pivot, as shown at 30, to the supporting block 29. This pivotal mounting of the arm 28^a permits oscillation of said arm about its support pivot 30 to allow escape of the crossing vehicles upon the track as will be hereinafter set forth.

This arm 28^a is provided with a horizontally positioned pivot 31 and associated spring and stop means, generally indicated at 32, for permitting upward swinging of the arm 28^a upon encountering a passing vehicle during the downward movement of the arm. The spring and stop means comprises the coil spring 34 which may be mounted on the portion 35 of the gate 12, as shown, and which may have its ends engageable with the surfaces of said portion 35 and said arm 28^a for normally urging said arm into extended alinement with the portion 35 about the pivot 31. Engagement between the shoulders 36

and 37 at the end of the arm 28^a and portion 35 respectively provide the stops which limit the downward swinging motion of the arm 28^a about the pivot 31 so that the arm will stop in alignment with the portion 35.

5 For stopping the swinging motion of the gate 12 in one direction about the pivot 30 as well as for automatically swinging said arm 28^a into its normally extended position

10 upon engagement therewith of a vehicle for passage therethrough, the same is provided with a spring 38 and stop means 39 and 40 analogous to the spring and stop means indicated at 32 for association with the pivot 31.

15 The spring 38 is of such construction as to urge the portion 35 about the pivot 30 in a counterclockwise direction as appears in Figure 2 so that the end portion 35^a will be moved into engagement with stops 39 and 40 positioned on the arm 26 and adapted to limit the

20 movement of the gate 12 to stop the same when in normal position.

25 As shown in Figure 3 the arm 28^a may be provided on the outer portion adjacent the extremity thereof or intermediate between the extremity and the pivot with a light 40^a, to indicate a gate closed position.

30 The gate 11 may be constructed similarly to the gate 12 if it is desired to control two streams of vehicle traffic. In this embodiment, however, we show it constructed of ordinary arms 42 and 43 integrally secured to the shaft 25, the arms 42 and 43 being adapted to secure thereon a gate arm of any desired 35 construction.

40 If the gate 12 is lowered until it engages with a vehicle passing therebelow, arm 28^a will rock about the pivot 31 on the portion 35 permitting the passage of the vehicle from 45 under the arm. After the passage of the vehicle from beneath the arm, the spring associated with the pivot 31 will automatically move the arm 28^a downwardly to its normal extended position until the stops constituted by the shoulders 36 and 37 are brought into 50 engagement.

55 If a vehicle is trapped upon the track by our gate when its arm is in the downward position or descending or raising the same can engage with the gate 12 and swing the gate about its pivot 30 to gain passage therethrough. The spring associated with the pivot 30 will automatically swing the gate to its normal extended position until the same engages with the stops 39 and 40.

60 It is understood that any number of our gates might be positioned at a railroad grade crossing and that in the ideal system or preferred embodiment a pair of these gates will be positioned at the grade crossing.

We claim:

65 In a crossing gate, a support, a body portion of a gate pivoted to the support, means for operating the body portion to upward and downward positions, a pivot pin mounted

upon said body portion, a main gate arm mounted thereon, said gate arm extending outwardly a substantial distance from said pin, stop means carried by said body portion, and spring means connected between said body portion and said gate arm for normally holding said arm against said stop means.
